HULLING-MACHINE.

1,305,811.

Specification of Letters Patent.

Patented June 3, 1919.

Application filed October 16, 1918. Serial No. 258,453.

To all whom it may concern:

Be it known that I, DAVID KRAUSE, a citizen of the United States, residing at Cleveland, in the county of Cuyahoga and State 5 of Ohio, have invented certain new and useful Improvements in Hulling-Machines, of which the following is a specification.

This invention relates to hullers particularly adapted for rice or barley, and designed to rapidly and effectively remove the hulls of such grain, the machine being capable of continuous operation, and the hulling being effected by the action of rotary disks or abrading wheels which revolve at a 10 high speed in one direction and which coöperate with alternating abrading rings or annuli which revolve slowly in the opposite direction, the grain flowing between the successive pairs or sets of abrading wheels.

20 The machine is also provided with improved feeding devices and with improved means for intermittently discharging the finished product.

25 Various other features and advantages of the machine will be apparent from the following description and the accompanying drawings.

In the drawings, Figure 1 is an end elevation of the machine. Fig. 2 is a central 30 vertical section. Fig. 3 is a face view of a "stop" mechanism controlling the feeding and discharging actions. Fig. 4 is a section on the line 4—4 of Fig. 2.

Referring specifically to the drawings, 22 35 indicates a horizontal shaft mounted in suitable bearings B in a frame C, and this shaft is connected by stepped pulleys 12 and 13 and belt to a counter-shaft 27. The shaft 22 carries the disks to be described, and the 40 shaft 27 drives the drum to be described, the present point being that by means of the step-pulleys 12 and 13 the relative speed of rotation of those parts may be varied, which is of some importance in obtaining 45 the proper action, especially on different kinds of grain.

The disks are indicated at 19, and are mounted on a hub 21 which is keyed to the shaft 22, the disks being spaced apart by 50 collars 23 on the hub. An end plate 23^a bolted to the hub, clamps the disks in place.

8 indicates an outer drum the periphery of which consists in the main of screen or wire fabric segments 24. One end plate of the 55 drum has a tubular or feeding neck 8^a which turns in a ring bearing 8^b on the frame.

The other end plate of the drum has a hub bearing at 8^d at the opposite end of the frame. Bolts 8^c connect the opposite end plates of the drum, and a collecting shield 60 or shell D surrounds the periphery of the drum from which it is spaced, and leads to an outlet spout E. 20 are segmental abrading members which are fastened to the periphery of the drum and project inwardly 65 between the respective disks 19 and which coöperate with those disks to hull the grain flowing through the spaces between. The disks 19 and the segments 20 will preferably be made of suitable abrading material, and 70 as heretofore indicated the disks 19 rotate at high speed in one direction and the segments 20 will revolve at low speed in the opposite direction.

The whole grain is fed into the neck of the 75 drum through a chute 18 from a hopper 7. The inlet to the hopper 7 from the spout 14 is controlled by a swinging valve 15, and the outlet from the hopper 7 to the chute 18 is controlled by a swinging valve 17. These 80 valves are operated by a cam mechanism actuated by the stop motion shown in Fig. 3 particularly. This comprises a disk 10 fastened to the end plate of the drum 8 and having a pair of circular face grooves 29 85 which terminate adjacent to the tooth 30 adapted to engage the pins 28 of the disk 11, and the pins 28 enter and leave the grooves 29 through gates 29^a adjacent to tooth 30, the whole forming a stop motion or escape- 90 ment for giving intermittent rotary movement to the disk 11. This disk is mounted on a shaft 11^a which is geared by pinions 6 to a cam gear 9 having a face cam groove from which motion is communicated 95 through levers and links 16 and 17^a to the valves 15 and 17 respectively, the action being to open and then close the valve 15, and then to open and close the valve 17, to feed the contents of the hopper 7 into the ma- 100 chine. The feed may be varied by changing the proportions of the pinions 6.

The periphery of the drum 8 is provided, between the ends of the segments 20, with gates 35 which may be opened intermittently 105 to allow the escape of the material into the discharge casing D. These gates are mounted on rock shafts 34 which extend through the end plate of the drum 8 and each carries an arm 33 adapted to be tripped, against the 110 tension of the spring 39, by a tripper 32 which slides in and out in guides 40 on the

frame and is operated by a lever 31 connected at its lower end to the tripper and provided at its upper end with a roller 31^a which runs in cam groove 9^a on the inner side of the cam wheel 9. The arm 33 when tripped is engaged by a pawl 36 and the door 35 is held open until the pawl is released. This release is effected by a cam 37 on the frame engaging a roller 38 on the pawl and throwing the pawl out to allow the spring 39 to return the gate to its closed position. These parts are so located that each gate remains open about $\frac{1}{4}$ of a revolution.

10 The drum is driven from the counter-shaft 15 27 by a pinion 26 engaging the ring gear 25 on the end plate of the drum.

By proper adjustment of the gearing the speed of the machine and the feed and discharge may be regulated as desired. The 20 use of hulling disks rotating in one direction alternating with hulling segments revolving therebetween in the opposite direction results in a very efficient hulling action and the action of the machine may be continuous, since the machine is automatically and continuously fed and the material discharged as the operation proceeds, and the machine does not have to be stopped to discharge it.

30 The grain which is fed in through the hub of the drum finds its way in and out between the attrition members 19 and 20, by which it is hulled, and its flow is assisted or permitted by the spaces between the ends of 35 the segments 20, which permit the grain to cross or pass from one end of the drum to the other, whereby all of the attrition members are active in the hulling process or operation.

40 I claim:

1. A rotary huller comprising a set of rotary attrition disks spaced apart, a rotary

drum inclosing said disks, and a set of laterally-spaced attrition segments projecting inwardly from the periphery of the drum 45 and between said disks, said segments being also spaced apart at their ends, and the drum having valved discharge outlets in the spaces between said ends.

2. A rotary huller comprising a set of 50 rotary attrition disks spaced apart, a rotary drum surrounding said disks and provided with a plurality of circumferentially spaced attrition members projecting between said disks and valve means to periodically discharge hulled material through the wall of the drum, from the spaces between said members.

3. The combination with a rotary huller 60 having a drum and circumferentially spaced segments in the interior thereof, and located between the ends of said segments, discharge doors in the wall thereof, of means automatically actuated by the rotation of the drum to open and close said doors, said 65 means including a stop motion to produce intermittent operation of the doors.

4. The combination with a rotary huller having a drum and discharge doors in the peripheral wall thereof, said doors having 70 crank arms connected thereto, of a tripper movable into the path of the arms to strike the same and open the doors, means to automatically operate the tripper, pawls engageable with said arms to hold the doors 75 open during part of the rotation, means to disengage the pawls and release the doors, and springs to close the doors.

In testimony whereof, I do affix my signature in presence of two witnesses.

DAVID KRAUSE.

Witnesses:

JOHN A. BOMMARDT,
L. LOUIS MALM.
